UNITED STATES PATENT OFFICE.

CHARLES F. LINDENMUTH AND RAYMOND A. HANLEY, OF ARISTES, PENNSYLVANIA.

MINER'S DRILL.

1,178,402.

Specification of Letters Patent.

Patented Apr. 4, 1916.

Application filed September 11, 1915. Serial No. 50,241.

To all whom it may concern:

Be it known that we, CHARLES F. LINDENMUTH and RAYMOND A. HANLEY, citizens of the United States, residing at 5 Aristes, in the county of Columbia and State of Pennsylvania, have invented new and useful Improvements in Miners' Drills, of which the following is a specification.

The invention relates to drills, and more 10 particularly to the class of detachable bit drills for mining purposes.

The primary object of the invention is the provision of a drill of this character wherein in the bits are detachably mounted so that 15 either two, three or five bits can be used, as the occasion may require.

Another object of the invention is the provision of a drill of this character wherein in the bits and the chuck of the drill are 20 of novel form for the mounting of the said bits in the chuck and the fastening of the same.

A further object of the invention is the provision of a drill of this character which 25 is simple in construction, thoroughly reliable and efficient in operation, strong, durable, and inexpensive in manufacture.

With these and other objects in view, the invention consists in the construction, combination and arrangement of parts as will be hereinafter fully described, illustrated in 30 the accompanying drawing, and pointed out in the claim hereunto appended.

In the drawing:—Figure 1 is a side elevation of a drill constructed in accordance with the invention. Fig. 2 is a view similar to Fig. 1, looking at right angles thereto. Fig. 3 is a fragmentary vertical longitudinal sectional view through the drill. Fig. 4 is 40 a perspective view of one of the bits. Fig. 5 is a sectional view on the line 5—5 of Fig. 1.

Similar reference characters indicate corresponding parts throughout the several 45 views in the drawing.

Referring to the drawings in detail, the drill comprises a solid shank 10 having formed at one end external threads 11 for the detachable fastening thereon of a 50 tubular handle 12, while at the opposite end of the shank 10 is formed the chuck 13 having therein the substantially key-hole shaped slots 14 and 15, respectively, which

are disposed at right angles to each other, the slot 15 being of greater length than the 55 slot 14, and in the external surface of the chuck is an annular groove 16 which intersects the slots 14 and 15 for a purpose presently described. Detachably fitted in the chuck 13 are the bits 17 and 18, respectively, 60 each being formed with an enlarged inner end 19 correspondingly shaped to the slot for receiving the same, and formed in the chuck. The bit 18 is provided with a central bifurcation 20 which is correspondingly 65 shaped to the cross section of the blade 17 for receiving the latter when the bit 18 is inserted in the chuck.

The bit 17 is formed with a medial cutting wing 21 and outer cutting prongs 22, while 70 the blade 18 is formed with the cutting prongs 23 similar to the prongs 22. Formed in the chuck 13 and in the blade 18 are registering grooves 24, while formed in the bit 17 is an opening 25 adapted to align 75 with the grooves 24, and through these grooves 24 and opening 25 is passed a cotter pin 26 which has the bent outer end 27 engaged in the groove 16, and this cotter pin serves to securely fasten the bits 17 and 80 18 in the chuck, yet they can be readily detached so that either one or both of the bits can be used.

From the foregoing description, taken in connection with the accompanying drawing, 85 the construction and manner of operation of the device will be clearly understood, and therefore a more extended explanation has been omitted.

What is claimed is:—

A drill of the class described comprising a shank having substantially keyhole shaped slots in one end thereof at right angles to each other, one of the slots being of greater length than the other for communication 95 with each other, bits having enlarged inner ends correspondingly shaped to the inner ends of the slots for detachable engagement therein, one of the bits being of greater length than the other, said longer bit being 100 bifurcated medially thereof for the intersection of the other bit, whereby the same will be disposed at right angles to each other, a medial wing formed on the outer end of the shorter blade and having an outer cutting edge, outer prongs formed at opposite 105

sides of the wing on said shorter blade and having inwardly beveled cutting edges, cutting prongs formed on the longer blade and having inwardly beveled cutting edges, said longer blade, and the wall of the slot receiving the same being formed with registering channels respectively, and a pin engaged

in said channels for locking the blade in the slot.

In testimony whereof we affix our signatures.

CHARLES F. LINDENMUTH.
RAYMOND A. HANLEY.
